ATTACHMENT FOR MEASURING TAPES

Emmitt L. Stewart, Oklahoma City, Okla., assignor to P. P. Williams and C. L. Purdue

Application March 8, 1934, Serial No. 714,707

2 Claims. (Cl. 15—210)

This invention relates to improvements in measuring devices and pertains particularly to an attachment for a steel gauge tape.

The primary object of the present invention is to provide a device for attachment to the steel tapes which are used for measuring oils, gasoline or other liquids in tanks, which will operate as the gauge is rewound after use, to thoroughly wipe and dry the tape and thereby prevent the fluid from attacking and destroying the same.

A further object of the invention is to provide an attachment of the character described, for steel tapes, which may be readily applied to the frame of the standard types of tapes which are at present on the market, without making any alteration in the construction of the tape frame.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:—

Figure 1 is a view partly in side elevation and partly in section of a device embodying the present invention, showing the same applied.

Figure 2 is a sectional view taken on the line 2—2 of Figure 1.

Figure 3 is a horizontal section taken on the line 3—3 of Figure 1.

Figure 4 is a view in perspective of the rubber blocks showing the same separated.

Referring to the drawing wherein like numerals of reference designate corresponding parts throughout the views, the numeral 1 indicates generally the frame portion of a steel gauge tape, of which there are several different types on the market at the present time. Within this frame is wound upon a suitable spindle the steel tape 2 and on one side of the frame is a shiftable handle element 3 by which the tape is rewound after it has been unwound for use. At one end of the frame 1, there is attached a handle 4, the usual method of attaching such handles being by the use of a screw of some character, which is secured in the handle and threaded into the frame or which may be passed through an aperture in the frame from the inside of the latter into the handle, thus making it possible to remove the handle from the frame. This fact is

taken advantage of in connection with the present invention for attaching the same to the frame for use.

The device embodying the present invention comprises an arcuate plate, which is indicated as a whole by the numeral 5. This plate is preferably of greater width at one end than at the other, and at the narrower end, a portion of it is formed perfectly flat, as indicated at 6, and has an aperture 7 therethrough. This flat portion of the plate 5 is disposed against the end of the frame 1 after removing the handle 4, so that the securing device of the handle may be passed through the aperture 7 and thus secure the plate in operative position.

The plate 5 is formed to be concentric with the tape when the latter is rolled up and the other or broad end of the plate has the portion 8 arranged to extend outwardly from the tape 2 substantially radially thereof. This broad terminal end portion 8 has disposed against one face one of two rubber blocks which are indicated by the numerals 9. These blocks 9 are made of an oil treated rubber so that they will not deteriorate from contact with oil, as ordinary rubber will do. The confronting faces of these blocks 9 have cut out areas formed midway between the ends of the blocks as indicated at 10. These areas are formed across the adjacent corners of the blocks so that there is thus formed a V-shaped recess which has its widest side directed toward the tape 2. The V is closed at its narrowest end but the tape 2 is located between the blocks, as illustrated, passing from the tape into the V-shaped opening and then between the blocks at the apex of the opening to the opposite sides of the blocks. Upon the outer side of the outer one of the blocks 9, the metal plate 11 is positioned and through this plate, the adjacent ends of the blocks 9 and the portion 8 of the plate 5, pins or bolts 12 are passed, each of which receives on one end the threaded nut 13 which bears against the plate 11 and thus provides a means for increasing the pressure between the contacting block faces.

Tapes of the character herein described usually have a hook such as is indicated by the numeral 13 upon the free end. This hook is provided for the attachment of a weight to the tape and it is disposed on the opposite side of the blocks 9 from the wound tape. It will thus be obvious that the tape, as it is unwound, will be drawn off between the blocks, and due to the fact that it enters between the blocks by way

of the recesses or openings 10 therein, very little resistance will be set up by the rubber to its passage. However, in rewinding, the frictional contact of the narrow edges of the blocks against the opposite faces of the tape, will cause the rubber blocks to bind against the tape and thus wipe the same dry of oil or water or any other fluid in which the tape may have been dipped so that the tape, when rewound, will be perfectly dry and will not be rusted by the liquid into which it was dipped.

What is claimed is:—

1. A wiping attachment for a rolled tape having a carrying frame, comprising an arm, means for attaching the arm at one end to the frame, said arm being arcuate and curving about the rolled tape carried by the frame, a pair of yieldable wiper bodies disposed in side by side contacting relation upon the free end of the arm, said tape being drawn between said bodies, a plate engaging one of the bodies in opposed relation to the arm, and securing elements passing through the plate, the bodies and the arm at either side of the tape for drawing the bodies

tightly together in wiping contact with the two sides of the tape.

2. A wiping attachment for a rolled tape having a carrying frame, comprising an arm of arcuate design, means for attaching one end of the arm to said frame whereby the arm extends substantially in a circumferential direction with respect to the rolled tape, the other end of the arm terminating in a straight portion directed away from the tape, a pair of threaded screw members extending through the said straight terminal portion of the arm in spaced parallel relation, a pair of yieldable wiper bodies having said screws extending therethrough, the wiper bodies having two faces in contacting relation with portions of the contacting faces cut away to form a recessed area, the said tape being slideable between the contacting faces of the bodies, and a nut threadably engaged on each of said screws upon the opposite sides of the bodies from the arm and normally maintaining the bodies in firm contact, the said tape passing between the bodies between said screws.
